EARNEST S. SPEARMAN, OF PELZER, SOUTH CAROLINA, ASSIGNOR TO BAHAN TEXTILE MACHINERY COMPANY, OF GREENVILLE, SOUTH CAROLINA, A CORPORATION OF SOUTH CAROLINA

SHAFT BEARING

Application filed December 31, 1929. Serial No. 417,769.

This invention seeks to provide means whereby the alinement of a shaft may be maintained and wear in the bearings compensated. While the invention is designed primarily for use in connection with the cam shafts of looms, it may be advantageously applied to any and all shafts. In looms a cam shaft is provided in the lower portion of the loom frame and carries a relatively large gear which meshes with a smaller gear upon a shaft immediately above the cam shaft, the cam shaft being carried by bearings mounted upon the frame. In time the lower portion of the bearing wears and the cam shaft 5 also wears so that the shaft drops and the gear thereon fails to mesh properly with the upper gear, and it is the object of the present invention to provide a simple and efficient attachment, independent of and separate from the bearing whereby said bearing may be adjusted so as to maintain the proper position of the shaft. The invention is illustrated in the accompanying drawing and will be hereinafter fully set forth and particularly defined.

In the drawing:

Figure 1 is an elevation of a portion of a loom frame showing the present invention applied thereto, and 30 Fig. 2 is a transverse section on the line 2—2 of Fig. 1.

The loom frame may be of any usual or approved form and a portion of the same is indicated at 1, the frame being provided with vertically extending slots 2 and having its lower portion spanned by a journal box 3 which fits closely over the lower portion of the frame, as clearly shown in Fig. 2. Securing bolts 4 are inserted through the lower portion of the journal box and through the slots 2 so that the box may be adjusted vertically to maintain the cam shaft in the proper position, a portion of the cam shaft being indicated at 5 in Fig. 2. A flange 6 is formed on the loom frame and this flange is arcuate in form, as shown clearly in Fig. 1, and extends from foot to foot of the frame so as to provide reinforcement for the supporting portion of the frame. In carrying out the present invention, there is provided a block 7

which has an arcuate lower side whereby it may rest directly upon the flange 6 and through this block is inserted a securing bolt 8 which also passes through the side of the loom frame to hold the block against end-wise movement. Threaded into the upper side of the block are set bolts or posts 9 which project above the block and have their heads 10 bearing directly against the lower edge of the journal box 3. Lock nuts 11 are mounted upon the bolts and rest upon the top of the block 7, as shown, so that the bolts will be locked in a set position.

It is thought the function of the device will be apparent from what has been said. In time the shaft receiving recess or groove in the journal box wears under the thrust imposed thereon by the operation of the loom and as it wears the shaft, of course, tends to drop so that eventually the gears will not properly mesh. Heretofore it has been necessary to stop the loom and apply a complete new journal box to remedy this condition, but by the use of my device, which is independent of the journal box or bearing and is attached to the frame beneath the bearing and in vertical alinement therewith the shaft can be adjusted without stopping the loom and in a very short time. When readjustment of the bearing becomes necessary, the bolts 4 are loosened and the lock nuts 11 are then released after which the adjusting bolts 9 are turned so as to move upwardly and this upward movement will, of course, be transmitted directly to the journal box so that the box will be moved upwardly and the proper meshing of the gears quickly attained. When the gears again mesh properly, the bolts 4 are again tightened and the lock nuts 11 turned home. The device is exceedingly simple and being in the nature of an attachment or accessory separate from and independent of the bearing may be readily applied to the bearing of any loom now in use as well as to the bearings of looms in course of construction without necessitating any structural changes or alterations in or to said bearing. The action is certain and efficient and when the bearing has been set it will remain in the set position for a long period and no attention need be given it until

it is observed that the gears have again failed to properly mesh.

Having thus described the invention, I claim:

- 5 1. As a new article of manufacture, a portable bearing adjuster for looms comprising a base for attachment to a support wholly beneath a bearing of the loom and independent of said bearing, spaced vertically disposed adjusting screws threaded in the base and adapted to bear against the lower portion of said bearing, and lock nuts threaded on the screws for engagement with the upper face of the base for holding the bearing in adjusted position.
- 10 2. As a new article of manufacture, a bearing adjuster separate from and independent of a bearing and adapted to be supported beneath and in vertical alinement with the bearing, said adjuster comprising a base having its lower portion shaped to conform to and adapted to be detachably connected with a support and its upper portion provided with a flat face having spaced threaded openings therein, vertically disposed adjusting screws engaging said threaded openings and having their upper ends provided with enlarged heads adapted to bear against the lower portion of said bearing, and lock nuts threaded on the adjusting screws beneath the heads thereof and adapted to bear against the flat face of the base for holding the bearing in adjusted position.
- 15 3. The combination with a supporting frame having a laterally extending reinforcing flange and provided with an adjustable bearing, of a bearing adjusting device separate from and independent of the bearing detachably mounted on the flange beneath and in vertical alinement with said bearing and comprising a base having its lower portion shaped to conform to and adapted to bear against the reinforcing flange and its upper portion provided with a flat face, the flat face of said base being formed with spaced threaded openings, vertically disposed adjusting screws threaded in said openings and having their upper ends provided with enlarged heads adapted to bear against the adjacent portion of the bearing, lock nuts threaded on said adjusting screws for engagement with the flat face of the base for holding the bearing in adjusted position, and means for securing the base to the supporting frame.

55 In testimony whereof I affixed my signature.
